CATHODE-RAY TUBE SUPPORTING STRUCTURE

Filed Dec. 17, 1949

CARL J. STEINKE
INVENTOR.

BY *Francis W. Crotty*
HIS ATTORNEY

tion of said enlarged end portion of said tube for encompassing said end portion and having an axial length approximately equal to said distance; a flange section formed integral with one end of said skirt section including a shoulder portion and a re-entrant lip portion for bearing against said face plate and providing an image frame therefor; and a depending flange section formed integral with the opposite end of said skirt section for mounting said structure to said chassis.

2. A flexible unitary structure for supporting on the chassis of a television receiver a cathode-ray tube having an enlarged end portion projecting a given distance beyond said chassis and enclosed by a face plate serving as an image screen to be viewed through an aperture in a panel of said receiver, said structure comprising: a skirt section for extending into said aperture having transverse dimensions corresponding approximately to the dimensions of said aperture, having a configuration corresponding to the configuration of said enlarged end portion of said tube for encompassing said end portion and having an axial length approximately equal to said distance; a flange section formed integral with one end of said skirt section including a shoulder portion and a re-entrant lip portion for bearing against said face plate and providing an image frame therefor; and a depending flange section formed integral with the opposite end of said skirt section for mounting said structure to said chassis.

3. A flexible unitary structure for supporting on the chassis of a television receiver a cathode-ray tube having an enlarged end portion projecting a given distance beyond said chassis and enclosed by a face plate serving as an image screen to be viewed through an aperture in the panel of said receiver, said structure comprising: a skirt section for extending into said aperture having transverse dimensions corresponding approximately to the dimensions of said aperture, having a configuration corresponding to the configuration of said enlarged end portion of said tube for encompassing said end portion and having an axial length approximately equal to said distance; a shoulder section formed integral with one end of said skirt and extending inwardly from said skirt over said face plate; a re-entrant

lip section formed integral with the inner periphery of said shoulder for bearing against said face plate and providing an image frame therefor; and a depending flange section formed integral with the opposite end of said skirt for mounting said structure to said chassis.

4. A flexible unitary structure for supporting on the chassis of a television receiver a cathode-ray tube having an enlarged end portion projecting a given distance beyond said chassis and enclosed by a face plate serving as an image screen to be viewed through a transparent viewing plate covering a circular aperture in a panel of said receiver, said structure comprising: a cylindrical skirt section for extending into said aperture, having a diameter corresponding approximately to the diameter of said aperture and for encompassing said enlarged end portion of said tube, and further having an axial length approximately equal to said distance; an annular shoulder section formed integral with one end of said skirt and extending inwardly from said skirt over said face plate; a re-entrant lip section formed integral with the inner periphery of said shoulder for bearing at opposite extremities against said viewing plate and said face plate and providing an image frame for said face plate; and a depending flange section formed integral with the opposite end of said skirt for mounting said structure to said chassis.

CARL J. STEINKE.
